UNITED STATES PATENT OFFICE.

PHILIP D. PARSONS, OF PHILADELPHIA, PENNSYLVANIA, ASSIGNOR TO SCOTT PAPER COMPANY, A CORPORATION OF PENNSYLVANIA.

MEANS FOR DISPENSING TOILET-PAPER.

1,354,511.

Specification of Letters Patent.

Patented Oct. 5, 1920.

Application filed June 2, 1918. Serial No. 101,203.

To all whom it may concern:

Be it known that I, PHILIP D. PARSONS, a citizen of the United States, and resident of Philadelphia, county of Philadelphia, and State of Pennsylvania, have invented an Improvement in Means for Dispensing Toilet-Paper, of which the following is a specification.

My invention has reference to method and means for dispensing folded paper articles from cabinets, and more particularly in respect to what are known as "interfold" paper towels. Heretofore, in cabinets for dispensing interfold paper towels, the exposed flap or tab of the lowermost towel, when pulled, will in the withdrawing of the said towel, bring into view and exposure a flap or tab of the next lowermost towel, and so on; but the objection to this manner of dispensing towels from a cabinet resides in the fact that a person may rapidly pull out all of the towels, and the tendency has been to waste the articles because they were too easy of withdrawal. The object of my invention is to provide a cabinet containing interfold towels with a hand manipulated means which, while normally permitting the depending tab or flap to be shielded against being directly grasped, may be manually manipulated through said means to bring the said tab or flap into an exposed position through a suitable aperture in the cabinet or case, whereby said tab may be grasped and the towel withdrawn, said act bringing the tab of the next lowermost towel into position to be similarly concealed or protected but also adapted to be projected into an exposed condition as in the first instance by the operation of the aforesaid manually operable means.

My invention consists in the aforesaid method and means for dispensing paper towels or similar articles from an inclosed cabinet, wherein the pulling of one towel brings a tab of the next towel into a shielded position and then to be brought into an exposed position by the manually operable means, so that there are two successive operations to position the flap of an inclosed towel whereby it may be positively withdrawn from the cabinet; all of which is more fully set out hereinafter and defined in the claim.

My invention will be better understood by

reference to the accompanying drawings, in which:

Figure 1 is a front elevation of the lower part of a dispensing cabinet (with a portion broken away), embodying one form of my improvements; Fig. 2 is a sectional side view of the same; Fig. 3 is a view similar to that of Fig. 1 showing another form of my improved invention; Fig. 4 is a sectional side view of the construction shown in Fig. 3; Fig. 5 is a side elevation (with a portion broken away) of another modification of my invention; and Fig. 6 is a sectional side view of the same.

2 is the cabinet and may be made in any suitable manner, said cabinet having adjacent to its lower part the supporting shoulders 3 and 4 upon which the package of interfold towels or articles 10 is supported. The rear shoulder portion 4 extends forward and downward as at 5, acting as a support over which the flap or tab 12 of the lowermost towel may hang. The lower portion of the cabinet 2 is further inclosed to normally shield the depending tab or flap 12 and at the same time to provide a slotted opening or aperture 6 through which the tab or flap may be projected by manually operated means. In Figs. 1 and 2, the lower extension 2^b of the cabinet is provided with a pivoted door or hinged portion 7, the same being hinged at the bottom as indicated at 8. This door 7 normally stands vertically and is held against outward swinging by means of the heels 11 adjacent to the hinge point, which act as stops to limit the outward movement of the said hinged portion 7. A spring 9 normally holds the part 7 in a vertical position, leaving a slight clearance above it to form the transverse slot 6 through which the paper tab or flap may extend, as indicated in dotted lines.

In the operation of the devices shown in Figs. 1 and 2, the tab 12 will hang down below the support 5 so that it comes back of the hinged door or part 7, as more fully shown in Fig. 2. If now the hinged door part 7 be pushed back into the dotted line position and then allowed to swing forward again, said hinged door portion will have passed back of the flap or tab 12, and then in returning to its initial position will push the flap 12 forward and hold it in a position which projects outwardly through the

slot 6, as indicated in dotted lines. This tab may then be pulled to remove the lowermost towel, but in so doing the under tab of the next lowermost towel will be drawn downward over the support 5 and into the position indicated at 12. In this way there are two manual operations necessary to bring the tab 12 into a position that it may be grasped, the first of these being due to the manipulation in withdrawing the previous towel, and the second operation being in manually actuating the hinged door 7 to bring the tab or flap 12 to the outside thereof.

15 In the case of the constructions shown in Figs. 3 and 4, the pivoted hinged part 7 of Figs. 1 and 2 is modified in the form indicated at 7^a which constitutes a transverse hinged frame having a forward projecting portion or blade 7^b at its free end. A spring 9^a of any suitable construction may be employed to hold the pivoted transverse hinged frame 7^a into a position back of the depending flap 12 as shown. Moreover, the lower part 2^b of the cabinet is formed rigid all the way around and provides the permanent transverse slot 6 through which the tab 12 is to be projected. It will now be understood that when the hand wheel 14 is rotated to throw the pivoted frame 7^a from the solid to the dotted line position, Fig. 4, the part 7^b of said frame strikes the tab 12 at a distance from its end and forces it through the transverse aperture 6, as indicated in dotted lines, and whereby it may be grasped. The projecting blade end 7^b of the frame 7^a is formed with a hooked portion at 13, the edge of the blade 7^b being bent backward as clearly indicated in Fig. 4. The purpose of this hooked shape or grooved edge is to provide means which would receive and hold the tab of the next sheet, if by any reason it attempted to pass through the aperture 6 when pulling out the lowermost sheet or towel. The operation of the hinged projector frame 7^a is had by means of a milled hand wheel 14 on shaft 8^a journaled in the bottom of the casing 2^b and to which said projecting blade is secured, the turning of the shaft operating to throw the blade end of the projecting frame into the dotted position, Fig. 4, against the tension of the spring 9^a to project the end 12 of the towel through the slot 6, as indicated in dotted lines.

55 When the hand wheel 14 is released, the spring 9^a returns the projector frame into the position indicated in solid lines, and the tab 12 of the next lowermost towel will be hanging in position to be projected through the aperture 6 upon the next manipulation.

60 Referring to Figs. 5 and 6, the means for bringing the tab 12 of the lowermost sheet into position to be grasped, consists of rollers 7^b which may be spring pressed together sufficiently to create a friction, and

these rollers may be operated by the hand wheel 14 of the outside of the case. Assuming the tab 12 to be between the rollers 7^b, as indicated in Fig. 6, the turning of said rollers will bring the lower end of the tab 70 down through the aperture 6 at the bottom of the supplemental casing 2^a which incloses the rollers, and the sheet may then be grasped by the fingers and pulled down between the rollers and withdrawn. In doing 75 this, the sheet will pull down the bottom tab of the next lowermost sheet and will draw the beginning of it through the rollers, as indicated in Fig. 6. It is not essential that this tab of the next sheet shall be drawn 80 through the rollers, as it will suffice if it rests upon them, as the turning of the rollers will feed it down so that it may be grasped. I have illustrated the several ways of the 85 mechanical feeding of the end of the tabs into position to be grasped, by way of example and not as restriction to the invention, as my improvements comprehend the employment of any mechanical devices for bringing the interfold tab through the casing so that it may be grasped and the sheet withdrawn, but in such manner that the withdrawal of the sheet through the aperture 6 will not draw the tab of the next sheet 90 through said aperture as has heretofore been 95 customary, the essential feature of my invention residing in the fact that a mechanical operation must be performed in addition to the manual act of pulling the paper to insure each individual sheet being 100 withdrawn. It is manifest that where the sheets can only be withdrawn with this additional manipulation of the dispensing device, there will be a tendency to restrict wasteful pulling out of the sheets such as 105 has heretofore been customary where one sheet after another could be rapidly pulled from the cabinet by merely grasping the ends with the fingers.

I have described my improved method 110 and means in that particularity which I deem to be the best exposition of my invention, and that which I prefer in commercial practice, but I do not restrict or confine myself to the minor secondary details as such 115 variations may be resorted to as matters of mechanical skill and without a departure from the spirit of the invention.

Having now described my invention, what I claim as new and desire to secure by Let- 120 ters Patent, is:—

In apparatus of the character stated, an inclosing case having a discharge aperture at the bottom and having supporting means for sustaining a stack of interfolded paper sheets at a distance above the discharging aperture so that the tabs of the sheets cannot fall by gravity, said case provided with supporting and guiding means below the supports for the paper package and sepa- 125 13

rate from the aperture and its walls for holding the depending tab in position close to the discharge aperture, in combination with manually controlled mechanical means arranged below said supporting and guiding means and operable from without the case for projecting a shielded depending tab of the paper through the discharge aperture whereby the same may be grasped for without drawing the paper sheet and forcibly liber-

ating the tab of the next sheet above and pulling it down over the supporting and guiding means into the initial inclosed and shielded position.

In testimony of which invention, I here- 15 unto set my hand.

PHILIP D. PARSONS.
